Application September 26, 1951, Serial No. 16,754

Term of patent 14 years

(Cl. D26—5)

To all whom it may concern:

Be it known that we, Anthony G. Horvath and William H. Kuner, residing at Dayton, Montgomery County, Ohio, and Robert L. Wolfe, residing at Springfield, Clark County, Ohio, all citizens of the United States, have invented a new, original, and ornamental Design for a Gearhead Motor, of which the following is a specification, reference being had to the accompanying drawing, forming a part thereof, in which:

Fig. 1 is a perspective view of a gearhead motor embodying our new design;

Fig. 2 is an end view thereof looking from the right of Figs. 1 and 3;

Fig. 3 is a top fragmentary plan view thereof; and

Fig. 4 is an end view thereof looking from the left of Figs. 1 and 3.

The dominant features of our design are shown in full lines in the drawing.

We claim:

The ornamental design for a gearhead motor, substantially as shown and described.

ANTHONY G. HORVATH.
WILLIAM H. KUNER.
